United States Patent Office

Des. 191,268
Patented Sept. 5, 1961

191,268

KNIFE POUCH

Earle W. Beyer, Delhi, Calif., assignor to Richard C. Soto, South San Francisco, Calif.

Filed Feb. 20, 1961, Ser. No. 64,003

Term of patent 14 years

(Cl. D22—6)

I claim:

The ornamental design for a knife pouch, substantially as shown.
